HUMIDITY CONTROLLER

Edward A. Russell, Chicago, Paul B. Parks, Oak Park, and William M. Smith, Chicago, Ill., assignors to Vapor Car Heating Company, Inc., Chicago, Ill., a corporation of New York

Application December 21, 1932, Serial No. 648,232

18 Claims. (Cl. 261—26)

This invention relates to certain new and useful improvements in humidity controlling apparatus, more particularly to apparatus adapted to be used in connection with a temperature regulating system for controlling the relative humidity in the air within an enclosed space such as a railway car.

While the invention in the form here shown by way of example is especially adapted for use in a railway car, the principal features thereof are equally adaptable for controlling the humidity in other types of enclosures. Briefly described, means is provided for circulating air from the enclosed space through a passage and thence back into the space. A sprayer, or other equivalent means for projecting additional moisture into the air, is positioned in this passage, and the pump for supplying water to the sprayer is driven by an electric motor, the operation of the motor being controlled by a humidostat positioned in the passage adjacent its entrance, that is in advance of the spraying device. This humidostat is in the form of a plurality of mercury-tube thermostats, certain of which are of the wet-bulb type so that the temperature recorded by the thermostat will vary according to the rate at which water is vaporized from a constantly moistened wick enclosing the bulb of the thermostat. A radiator, operating in conjunction with the heating system within the enclosed space, is also positioned in the passage so as to heat the air circulated through the passage, and a heat exchanger is provided in connection with this radiator for pre-heating the water delivered to the sprayer. Refrigerating means may also be positioned in the passage for cooling the air when such treatment is desirable.

The principal object of this invention is to provide an improved humidity controlling apparatus of the type briefly described hereinabove and disclosed more in detail in the specifications which follow.

Another object is to provide a humidifying apparatus controlled by a wet bulb mercury tube thermostat.

Another object is to provide a humidifying apparatus controlled by a pair of wet-bulb thermostats functioning so that the humidifier will operate to add moisture to the air until the wet bulb temperature exceeds a certain predetermined maximum, and will then be caused to cease operating until the wet bulb temperature has fallen below a certain predetermined minimum, whereupon the humidifier will again be placed in operation and will continue to operate until the pre-

determined maximum wet bulb temperature has again been reached.

Another object is to provide an improved controlling means for a humidifier of the type described above comprising a dry bulb thermostat functioning to prevent the operation of the humidifier when the dry bulb temperature falls below a predetermined minimum.

Another object is to provide an improved humidostat assembly comprising a plurality of mercury tube thermostats certain of which are of the wet-bulb type so as to be responsive to changes in relative humidity.

Another object is to provide improved means for pre-heating the water delivered to the spraying device of the humidifier.

Another object is to provide an improved electric control circuit for a humidifying apparatus.

Other objects and advantages of this invention will be more apparent from the following detailed description of one approved form of apparatus constructed and operating according to the principles of this invention.

In the accompanying drawings:

Fig. 1 is a longitudinal vertical section through a portion of a railway car equipped with this improved humidifying system.

Fig. 2 is a perspective view showing the radiator and water-preheater.

Fig. 3 is a side elevation, partially in vertical section, showing the thermostat assembly.

Fig. 4 is a front elevation of the assembly shown in Fig. 3, also partially in vertical section.

Fig. 5 is a wiring diagram showing the thermostatically controlled circuit governing the operation of the pump-motor.

Referring first to Fig. 1, the railway car indicated generally at 1 encloses the usual space or chamber 2, and it is the function of the apparatus hereinafter described to regulate the temperature and humidity of the air within this chamber 2. The passage or chamber 3, usually positioned in one upper end portion of the car, houses the principal elements of the humidifying apparatus and also certain temperature regulating apparatus. The fan or blower 4 draws air into passage 3 through the inlet opening 5 covered by grille 6 and projects this air back into the chamber 2, preferably through a discharge passage 7 provided with a plurality of grilles 8 positioned at different locations throughout the length of the car. A certain proportion of additional fresh air may be drawn in from outside the car through the valved inlet port 9 and carried through the humidifying and

temperature regulating apparatus and then projected into the car through the discharge ports 8.

At 10 is indicated one of the radiators for heating the air within chamber 2, the supply of heating medium to this radiator, or group of radiators, being controlled by the valve indicated at 11. A radiator 12 (see also Fig. 2) is positioned within the passage 3 and supplied with heating medium through the pipe 13 leading from the 10 distributing valve 14, the heating medium and condensate returning through pipe 15 from the radiator 12 to the valve 14 and thence to the vapor regulator, when a vapor heating system of well known type is used. While a steam or 15 vapor heating system is here shown by way of example, it is to be understood that other types of heating systems might be used in connection with the improved humidifying system herein-after disclosed. The valves 11 and 14 may be 20 automatically controlled, either separately or jointly by means of thermostatic apparatus responsive to temperature changes within the chamber 2, as is used in such systems. The radiator 12 merely functions to temper the air circulated 25 through passage 3, the air being further heated by the system indicated generally at 10 after it is discharged into the chamber 2. When it is desirable to cool instead of to heat the air, a suitable refrigerating system may be used to 30 withdraw heat from the air circulating through passage 3, such heat-absorbers being indicated by the coils shown at 16 and 17. It will be understood, of course, that the refrigerating system and the heating system are not intended to be 35 used simultaneously. The eliminator plates indicated at 18 and 19 are for the purpose of cleaning or removing dust from the air circulated through passage 3. These devices may be of any suitable form, for example spaced screens with 40 copper-wool therebetween, as well known in the art.

For the purpose of adding moisture to the air, a suitable spraying device indicated generally at 20 is positioned at some intermediate location in 45 passage 3, for example as here shown between the two cleaning devices 18 and 19. The sprayer comprises a plurality of nozzles 21 through which the water is discharged into the air, the water being supplied to the sprayer through pipe 22. The water discharged by the sprayer in excess of that taken up by the air is collected in a suitable pan 23. A drain pipe 24 has its upper open 50 inlet end 25 positioned a suitable distance below the top of pan 23 so that a substantially constant water level will be maintained within the pan. The excess liquid drains down through pipe 24 into a "make-up" or collecting tank 26, usually positioned beneath the car. Water is withdrawn from tank 26 by pump 27 and forced up through 55 pipe 28 to the spraying device. The pump 27 is driven by a motor 29. The operation of this motor is thermostatically controlled, as herein-after described, and when the motor is at rest the sprayer 20 ceases to operate.

60 Referring now more particularly to Fig. 2, it will be noted that the water supply pipe 28 leading from pump 27 connects into the pre-heater 30 from which leads the pipe 22 which supplies water to the sprayer 20. The pre-heater 30 is also connected into the return pipe 15 leading 65 from radiator 12. The pre-heater is of well known type comprising two intimately adjacent but non-communicating passages or sets of passages through one of which flows the heating medium and condensate from the radiator 12, and

through the other of which flows the water supply for the sprayer. Heat will be transferred from the vapor or condensate to raise the temperature of the water flowing to the spraying device so that the temperature of this water will more nearly approximate that of the air into which it is discharged.

The operation of the pump motor 29 is controlled by a thermostatic assembly or humidostat indicated generally at 31 (see Fig. 1) positioned in passage 3 near its inlet end so as to register the temperature and relative humidity of the air drawn into this passage through inlet 5 and inlet 9. The air drawn by fan 4 through the spraying and temperature adjusting mechanisms will pass in contact with this humidostat. This thermostatic assembly is shown more in detail in Figs. 3, 4 and 5 and comprises, in the present example, three separate thermostats 32, 33 and 34 of the mercury tube type. Each of these thermostats, like an ordinary thermometer, comprises a bulb 35 containing a quantity of mercury and a closed tube 36 extending upwardly from the bulb in which a mercury column 37 will rise and fall with temperature changes. Each thermostat is provided with a lower contact member which is in constant engagement with the mercury column and an upper contact member with which the mercury column will engage at a certain predetermined temperature. A control circuit is completed through the thermostat when the mercury column is in contact with both of the fixed contact members. The thermostat 32 indicates the ordinary dry bulb temperature of the air passing in contact therewith and its upper fixed contact 38 is so positioned that the mercury column will engage therewith at a certain minimum temperature, for example 60° Fahrenheit. The control connections (hereinafter described) are such that the humidifier will not be operative unless the dry bulb temperature of the air is above 60°, or the temperature for which thermostat 32 is adjusted. The bulbs 35 of thermostats 33 and 34 are enclosed by wicks 39 and 40 which are constantly supplied with water so that these thermostats will register wet-bulb temperatures. Some of this water will be evaporated and carried away by the air flowing in contact with the thermostat, thus withdrawing heat from the bulb and causing a lower temperature to be registered by the thermostat. It will be apparent that the drier the air, or the lower its relative humidity, the higher will be the rate of evaporation from the wick and the more will the thermostat reading be lowered below a corresponding dry bulb reading. The higher the relative humidity of the air, that is the more moisture already in suspension in the air, the lower will be the rate of evaporation from the wick and the less will be the divergence of the thermostat reading from that of a corresponding dry-bulb thermostat. The fixed upper contact members 41 and 42 of the thermostats 33 and 34 respectively are so positioned that the thermostat 33 will complete its circuit at a wet-bulb temperature of, for example, 59° Fahrenheit whereas the thermostat 34 will complete its circuit at a somewhat lower wet-bulb temperature, for example 57° Fahrenheit. These wet-bulb temperatures correspond approximately to a dry-bulb temperature of 70° Fahrenheit when the air has a desired relative humidity of approximately 50%.

The group of thermostats is preferably supported on a panel 43 carried by a suitably supported bracket member 44 (see Figs. 3 and 4). The lower portions of wicks 39 and 40 extend into a

receptacle 45 which is constantly filled to a certain level with water, preferably by being connected with pan 23 through a pipe connection 46, Fig. 1. The receptacle 45 might be a part of the pan 23 it only being essential that the wicks 39 and 40 be constantly maintained in a moistened condition.

The actuating and control circuits for pump motor 29 are shown in Fig. 5. When the relay coil 47 is energized, the core 48 will be drawn into the coil, and through stem 49 will close a main switch 50 and open an auxiliary switch 51. An actuating circuit for the motor will now be completed as follows: From positive main 52 through wire 53, main switch 50, wire 54, pump motor 29, and wire 55 to the negative main 56. When the coil 47 is deenergized, or insufficiently energized, the core 48 and stem 49 will be moved in the opposite direction by a suitable spring means or by gravity so as to open the main switch 50 and close the auxiliary switch 51. This will cause the pump motor 29 to cease operating. The relay coil 47 may normally be energized by current flowing over the following circuit: From positive main 52 through resistance 57, terminal 58, coil 47, terminal 59, wire 60, wire 61, thermostat 32, wire 62, resistance 63, and negative main 56. The resistances 57 and 63 are simply to cut down the strength of the current flowing through the relay coil and thermostats. It will be noted that current cannot flow over this circuit when the dry-bulb thermostat 32 registers a temperature below 60° Fahrenheit since the circuit will be broken through this thermostat. A very high resistance 64 is shunted across the thermostat 32 to prevent arcing when the circuit through this thermostat is broken. This resistance is too high to prevent the flow of sufficient current to cause the solenoid 47 to function.

With the parts in the positions shown in Fig. 5, the dry-bulb temperature is above 60° Fahrenheit but the wet-bulb temperature is below 59° Fahrenheit, indicating that there is insufficient moisture in the air. The solenoid 47 is energized and main switch 50 is closed so that the pump motor 29 will operate to cause the sprayer 20 to function and the humidity of the air is being increased. When the relative humidity of the air has been raised to the desired percentage, the wet-bulb thermostat 33 will register a temperature of 59° thus completing a shunt circuit around the solenoid coil 47 as follows: From terminal 58 through wire 65, wire 66, thermostat 33, and wire 60 to the terminal 59. This will cause the relay to be deenergized so that the main switch 50 will be opened and the pump motor will cease to operate. If only the single wet-bulb thermostat 33 were used, as soon as the wet-bulb temperature had fallen below 59° Fahrenheit this shunt circuit would be broken and the relay would again be energized to start the operation of the pump. However, at the same time that the main switch 50 is opened the auxiliary switch 51 is closed to complete a second shunt circuit through thermostat 34 as follows: From terminal 58 through wire 65, auxiliary switch 51, wire 67, thermostat 34, and wire 60 to terminal 59. This second shunt circuit acts as a holding circuit to prevent the re-closing of the motor-actuating circuit until the wet-bulb temperature has fallen below 57° Fahrenheit (or the temperature for which thermostat 34 is adjusted).

It will now be apparent that in the general operation of this device the humidifier cannot

operate unless the dry-bulb temperature of the air is above 60°, or the temperature for which thermostat 32 is adjusted. Below this temperature it is unnecessary to regulate the relative humidity of the air. The dry-bulb temperature will normally be maintained above this minimum so that the humidifier will be operative to add moisture to the air whenever the relative humidity falls below 45 percent to 50 percent in which case the wet-bulb temperature will fall below 57°, or the temperature for which thermostat 34 is adjusted. In this event the pump motor will be started and water will be forced through the sprayer 20. The humidifier will continue to function until the wet-bulb temperature has risen to or above 59° whereupon the pump will be stopped and the sprayer will remain inoperative until the wet-bulb temperature again falls below 57°. The use of the two wet-bulb thermostats 33 and 34 prevents a spasmodic on and off operation of the sprayer since the sprayer will continue to function for a sufficient period of time to be effective while the wet-bulb temperature is rising between 57° and 59°, and the sprayer will be kept out of operation while the wet bulb temperature is falling between 59° and 57°.

Approximately 25% of fresh air is usually admitted to the car through inlet 9, and it will be noted that this fresh air is mixed with the air drawn into passage 3 through inlet 5 from chamber 2, and that the thermostat assembly 31 is responsive to the temperature and humidity of this air mixture. After this air has been humidified, it is pre-heated by radiator 12 before it is discharged into the chamber 2 through openings 8. The spraying water is also pre-heated by means of heat exchanger 30 so that its temperature will approximate that of the air stream into which it is discharged.

In those climates or during those seasons when the outside temperature is such that the air within the car is to be cooled instead of heated, the heating system will obviously be inoperative and the refrigerating system will be operated to reduce the temperature of the air stream flowing through passage 3 by means of the refrigerating coils 16 and 17.

We claim:

1. A humidifying apparatus comprising a device for distributing water, a motor for operating the device, an actuating circuit for the motor, a main switch in the actuating circuit, and control mechanism for opening and closing the main switch comprising a relay which when energized holds the main switch closed, a normally closed energizing circuit for the relay, a shunt circuit for short-circuiting the relay, and a wet-bulb mercury tube thermostat in the shunt circuit.

2. A humidifying apparatus comprising a device for distributing water, a motor for operating the device, an actuating circuit for the motor, a main switch in the actuating circuit, and control mechanism for opening and closing the main switch comprising a relay which when energized holds the main switch closed, a normally closed energizing circuit for the relay, a shunt circuit for short-circuiting the relay, a wet-bulb mercury tube thermostat in the shunt circuit, a second circuit shunted around the relay, a second wet-bulb mercury tube thermostat in this second shunt circuit and operative to close its circuit at a lower temperature than the first mentioned thermostat, and a switch in the second

- shunt circuit that is closed by the relay when it is deenergized and the main switch is opened.
3. A humidifying apparatus comprising a device for distributing water, a motor for operating the device, an actuating circuit for the motor, a main switch in the actuating circuit, and control mechanism for opening and closing the main switch comprising a relay which when energized holds the main switch closed, a normally closed energizing circuit for the relay, a shunt circuit for short-circuiting the relay, a wet-bulb mercury tube thermostat in the shunt circuit, and a dry-bulb thermostat positioned in the relay energizing circuit and operative to open this circuit when the dry-bulb temperature falls below a predetermined minimum. -
4. A humidifying apparatus comprising a device for distributing water, a motor for operating the device, an actuating circuit for the motor, a main switch in the actuating circuit, and control mechanism for opening and closing the main switch comprising a relay which when energized holds the main switch closed, a normally closed energizing circuit for the relay, a shunt circuit for short-circuiting the relay, a wet-bulb mercury tube thermostat in the shunt circuit, a second circuit shunted around the relay, a second wet-bulb mercury tube thermostat in this second shunt circuit and operative to close its circuit at a lower temperature than the first mentioned thermostat, a switch in the second shunt circuit that is closed by the relay when it is deenergized and the main switch is opened, and a dry-bulb thermostat positioned in the relay energizing circuit and operative to open this circuit when the dry-bulb temperature falls below a predetermined minimum.
5. Apparatus for controlling the humidity within an enclosed space comprising an air passage communicating with the space, means for circulating air through the passage, means for distributing water into the air within the passage, and means for controlling the distributing means comprising a pair of wet-bulb mercury tube thermostats positioned in the passage, one thermostat functioning to put the distributing device in operation at a predetermined wet-bulb temperature, and the other functioning to stop the operation of the distributing device at a second predetermined wet-bulb temperature.
6. Apparatus for controlling the humidity within an enclosed space comprising an air passage communicating with the space, means for circulating air through the passage, means for distributing water into the air within the passage comprising a pump, a motor for driving the pump, an actuating circuit for the motor, and means for opening and closing the motor circuit comprising a relay, a control circuit for the relay, and a wet-bulb mercury tube thermostat positioned in the passage and connected in the control circuit.
7. Apparatus for controlling the humidity within an enclosed space comprising an air passage communicating with the space, means for circulating air through the passage, means for distributing water into the air within the passage comprising a pump, a motor for driving the pump, an actuating circuit for the motor, means for opening and closing the motor circuit comprising a relay, a control circuit for the relay, and a pair of wet-bulb mercury tube thermostats positioned in the passage and connected in the control circuit, one thermostat functioning to cause the motor to be actuated at one predetermined wet-bulb temperature and the other functioning to stop the motor at a predetermined higher wet-bulb temperature.
8. Apparatus for controlling the humidity within an enclosed space comprising an air passage communicating with the space, means for circulating air through the passage, means for distributing water into the air within the passage comprising a pump, a motor for driving the pump, an actuating circuit for the motor, means for opening and closing the motor circuit comprising a relay, a control circuit for the relay, and a pair of wet-bulb mercury tube thermostats and a dry-bulb thermostat all positioned within the passage, one wet-bulb thermostat functioning to cause the motor to be actuated at one predetermined wet-bulb temperature, the other wet-bulb thermostat functioning to cause the motor to stop at a predetermined higher wet-bulb temperature, and the dry-bulb thermostat functioning to prevent operation of the motor when the dry-bulb temperature of the air within the passage falls below a predetermined minimum. 80
9. Apparatus for controlling the humidity within an enclosed space comprising an air passage communicating with the space, means for circulating air through the passage, means positioned within the passage for changing the temperature of the air circulating therethrough, means for distributing water into the air within the passage comprising a pump, a motor for driving the pump, an actuating circuit for the motor, means for opening and closing the motor circuit comprising a relay, a control circuit for the relay, and a pair of wet-bulb mercury tube thermostats 100 and a dry-bulb thermostat all positioned within the passage, one wet-bulb thermostat functioning to cause the motor to be actuated at one predetermined wet-bulb temperature, the other wet-bulb thermostat functioning to cause the motor to stop at a predetermined higher wet-bulb temperature, and the dry-bulb thermostat functioning to prevent operation of the motor when the dry-bulb temperature of the air within the passage falls below a predetermined minimum. 95
10. Apparatus for controlling the humidity within an enclosed space comprising an air passage communicating with the space, means for circulating air through the passage, a radiator within the passage for heating the air passing therethrough, supply and return pipes for delivering heating medium to and from the radiator, means for adding moisture to the air comprising a spraying device positioned in the passage, a water supply pipe leading to the spraying device, 105 a heat-exchanger connected in the heating medium return pipe and the water supply pipe for preheating the water to be sprayed, a pump for forcing water to the spraying device, a motor for driving the pump, and a humidostat positioned in 110 the passage for controlling the operation of the motor. 120
11. Apparatus for controlling the humidity within an enclosed space comprising an air passage communicating with the space, means for 115 circulating air through the passage, a radiator within the passage for heating the air passing therethrough, supply and return pipes for delivering heating medium to and from the radiator, means for adding moisture to the air comprising 125 a spraying device positioned in the passage, a water supply pipe leading to the spraying device, a heat-exchanger connected in the heating medium return pipe and the water supply pipe for 130 preheating the water to be sprayed, a pump for forcing water to the spraying device, a motor for driving the pump, and a humidostat positioned in 135 the passage for controlling the operation of the motor. 140
12. Apparatus for controlling the humidity within an enclosed space comprising an air passage communicating with the space, means for 145 circulating air through the passage, a radiator within the passage for heating the air passing therethrough, supply and return pipes for delivering heating medium to and from the radiator, means for adding moisture to the air comprising a spraying device positioned in the passage, a water supply pipe leading to the spraying device, a heat-exchanger connected in the heating medium return pipe and the water supply pipe for 150 preheating the water to be sprayed, a pump for 150

- forcing water to the spraying device, a motor for driving the pump, a control circuit for the motor, a wet-bulb mercury tube thermostat positioned in the passage and connected in the control circuit, said thermostat comprising a wick, and means for moistening the wick from water discharged from the spraying device. 80
12. Apparatus for controlling the humidity within an enclosed space comprising an air passage communicating with the space, means for circulating air through the passage, and means for adding moisture to the air comprising a spraying device in the passage, a pan for collecting the water sprayed in excess of that absorbed by the air, a tank, an overflow drain pipe leading from the pan to the tank, a pump for forcing water from the tank to the spraying device, a motor for driving the pump, a control circuit for the motor, and a wet-bulb mercury tube thermostat positioned in the passage and connected in the control circuit, the thermostat comprising a wick which is moistened from the water collected in the pan. 85
13. Apparatus for controlling the humidity within an enclosed space comprising an air passage communicating with the space, means for circulating air through the passage, and means for adding moisture to the air comprising a spraying device in the passage, a pan for collecting the water sprayed in excess of that absorbed by the air, a tank, an overflow drain pipe leading from the pan to the tank, a pump for forcing water from the tank to the spraying device, a motor for driving the pump, a control circuit for the motor, and a wet-bulb mercury tube thermostat positioned in the passage and connected in the control circuit, and a receptacle connected with the pan and supplied with water therefrom, the thermostat comprising a wick which extends into the water within the receptacle. 90
14. Apparatus for controlling the humidity within an enclosed space comprising an air passage communicating with the space, means for circulating air through the passage, and means for adding moisture to the air comprising a spraying device in the passage, a pan for collecting the water sprayed in excess of that absorbed by the air, a tank, an overflow drain pipe leading from the pan to the tank, a pump for forcing water from the tank to the spraying device, a motor for driving the pump, a control circuit for the motor, and a pair of wet-bulb mercury tube thermostats positioned in the passage and connected in the control circuit, and a receptacle connected with the pan and supplied with water therefrom, each thermostat comprising a wick which extends into the water within the receptacle. 95
15. A humidifying apparatus comprising a device for distributing water, electrically controlled mechanism for supplying water to the distributing device, said mechanism comprising an actuating circuit, a main switch in the actuating circuit, and control mechanism for opening and closing the main switch comprising a relay which when energized holds the main switch closed, a normally closed energizing circuit for the relay, a shunt-circuit for short-circuiting the relay, and a wet-bulb mercury-tube thermostat in the shunt circuit. 100
16. A humidifying apparatus comprising a device for distributing water, electrically controlled mechanism for supplying water to the distributing device, said mechanism comprising an actuating circuit, a main switch in the actuating circuit, and control mechanism for opening and closing the main switch comprising a relay which when energized holds the main switch closed, a normally closed energizing circuit for the relay, a shunt-circuit for short-circuiting the relay, a wet-bulb mercury-tube thermostat in the shunt circuit, a second circuit shunted around the relay, a second wet-bulb mercury tube thermostat in this second shunt circuit and operative to close its circuit at a lower temperature than the first mentioned thermostat, and a switch in the second shunt circuit that is closed by the relay when it is deenergized and the main switch is opened. 105
17. A humidifying apparatus comprising a device for distributing water, electrically controlled mechanism for supplying water to the distributing device, said mechanism comprising an actuating circuit, a main switch in the actuating circuit, and control mechanism for opening and closing the main switch comprising a relay which when energized holds the main switch closed, a normally closed energizing circuit for the relay, a shunt-circuit for short-circuiting the relay, a wet-bulb mercury-tube thermostat in the shunt circuit, and a dry bulb thermostat positioned in the relay energizing circuit and operative to open this circuit when the dry bulb temperature falls below a predetermined minimum. 110
18. A humidifying apparatus comprising a device for distributing water, electrically controlled mechanism for supplying water to the distributing device, said mechanism comprising an actuating circuit, a main switch in the actuating circuit, and control mechanism for opening and closing the main switch comprising means for holding the switch closed while the wet-bulb temperature of the air is rising from a predetermined minimum to a predetermined maximum, means comprising a wet-bulb mercury tube thermostat for opening the main switch when the predetermined maximum wet-bulb temperature is reached, and means comprising a second wet-bulb thermostat for holding the switch open while the wet-bulb temperature is falling to the predetermined minimum. 115
